UNITED STATES PATENT OFFICE.

GEORGE B. ADAMS, OF CHICAGO, ILLINOIS.

TELEPHONE-INDEX.

No. 828,914.

Specification of Letters Patent.

Patented Aug. 21, 1906.

Application filed December 5, 1905. Serial No. 290,476.

To all whom it may concern:

Be it known that I, GEORGE B. ADAMS, a citizen of the United States, residing at Chicago, in the county of Cook and State of Illinois, have invented a new and useful Telephone-Index, of which the following is a specification.

This invention relates to telephone-indexes.

The object of the invention is to provide an index for individual use which shall be adapted for ready connection with or disconnection from the mouthpiece of a telephone-transmitter and in which the names and telephone-numbers of various subscribers shall be so exhibited as to be readily found with the minimum loss of time.

With the above and other objects in view, as will appear as the nature of the invention is better understood, the same consists in the novel construction and combination of parts of a telephone-index, as will be hereinafter fully described and claimed.

In the accompanying drawings, forming a part of this specification, and in which like characters of reference indicate corresponding parts, Figure 1 is a perspective view of a telephone, exhibiting the index of the present invention combined with the mouthpiece of the transmitter thereof. Fig. 2 is a perspective detail view of the index.

Referring to the drawings, T designates a telephone of any preferred construction, and M the mouthpiece of the transmitter. These parts may be of the usual or any preferred construction, and therefore need no detailed description. The invention resides in the novel form of index to be detachably combined with the mouthpiece and to bear the names and telephone-numbers of any desired number of subscribers with whom the owner of the telephone may transact business or communicate messages.

The index comprises an attaching member 1 and a plurality of cards 2, which are suitably ruled and indexed, each card bearing a letter of the alphabet and the series of cards being lettered in sequence from "A" to "Z." The attaching member 1 is constructed from a length of resilient wire of any desired gage and comprises a pair of gripping elements 3 and 4, that are connected by a coil 5, that operates to increase the resiliency of the member. The element 3 terminates in a loop 6, while the element 4 extends some distance beyond the loop 6 and terminates in an L-

shaped card-carrying member 7, upon which the cards are strung, the latter member having its end formed into a loop 8, constituting a stop that operates to prevent accidental separation of the cards.

The elements 3 and 4 are disposed approximately in the same plane, so that when the attaching member is positioned upon the phone it will hang in the proper position to permit ready access to the cards. The orifices in the cards through which the member 7 projects are of a size somewhat larger than the stop 8, thus to permit of one or more of the cards being removed for the purpose of adding new names thereto as may be necessary from time to time. In order to prevent the cards from accidentally working loose from the carrying member, the orifice 9 in the outer card 10 is elongated and disposed longitudinally of the length of the card and at right angles to the stop 8, so that without turning the outer card at right angles to its normal position it cannot become detached from the carrying member. This is a feature of importance, inasmuch as without this provision a person hurriedly using the index might detach the cards from the carrying member and cause their loss. Generally it will be preferred to make the card 10 of some material tougher than the cards 2, such as celluloid, aluminium, or other metal, this being advisable on account of the constant wear at the orifice 9, resulting from the swinging of the cards.

Where names of telephone subscribers are printed on the cards by type-writer, it will be necessary to remove them from the carrying member; but where the names are entered with pen and ink this will not be necessary, as the entire device may be lifted from the mouthpiece of the telephone and opened to the proper card to receive the data.

It will be seen from the foregoing description that although the improvements herein defined are simple in character they will be thoroughly efficient in use for the purpose designed and may be readily used in connection with an ordinary telephone without requiring any change whatever in its structural arrangement.

I claim—

1. A telephone-index comprising an attaching member embodying a pair of gripping elements, one of which terminates in a carrying member provided with a terminal stop,

and suitably-indexed cards threaded on the carrying member, the outer one of which is provided with means for engaging the stop.

2. A telephone-index comprising an attaching member embodying a pair of curved gripping members connected by a coil, one of the members terminating in an L-shaped carrying member having a terminal stop, and a plurality of alphabetically-indexed cards strung upon the carrying member, the outer one of which is adapted to be held against accidental separation from the member.
3. As a new article of manufacture, an at-

taching member for telephone-indexes embodying a pair of curved gripping members connected by a loop or coil, one of which members terminates in an L-shaped carrying member having a terminal stop.

In testimony that I claim the foregoing as my own I have hereto affixed my signature in the presence of two witnesses.

GEORGE B. ADAMS.
